UNITED STATES PATENT OFFICE.

CHARLES H. LEWY, OF NEW YORK, N. Y., ASSIGNOR TO CHARLES H. LEWY
AND MEYER JONASSON, OF SAME PLACE.

SPOOL-RACK FOR SEWING-MACHINES.

SPECIFICATION forming part of Letters Patent No. 448,528, dated March 17, 1891.

Application filed October 18, 1890. Serial No. 368,609. (No model.)

To all whom it may concern:

Be it known that I, CHARLES H. LEWY, a subject of the Emperor of Germany, at present residing in the city of New York, in the county and State of New York, United States of America, have invented a new and useful Improvement in Spool-Holders, of which the following is a full, clear, and exact description.

My invention relates to an improved spool-holder, and has for its object to provide a rotatable table adapted to contain a number of spools, each capable of independent rotation, and also to provide a means whereby the spools, while free to turn, cannot be removed from the table except by a person or persons possessing the key of the locking device employed in connection with the spool-holder.

A further object of the invention is to provide a means for expeditiously and conveniently removing empty spools from the table and substituting therefor filled spools, and to construct a device in a simple, durable, and economic manner, capable of being manipulated successfully by any person of ordinary intelligence.

The invention consists in the novel construction and combination of the several parts, as will be hereinafter fully set forth, and pointed out in the claim.

Reference is to be had to the accompanying drawings, forming a part of this specification, in which similar figures and letters of reference indicate corresponding parts in all the views.

Figure 1 is a side elevation of the improvement with parts in section and as applied to the arm of a sewing-machine. Fig. 2 is an inverted sectional plan view of the same on the lines 6 6 of Fig. 1; and Fig. 3 is a detail perspective view of a guide used in connection with the spools.

The prime object of the invention is to provide a convenient spool-holder intended to take the place of the ordinary spindle or pin now usually employed on sewing-machine arms to support the spool carrying the needle-thread. The spool-holder supports a series of spools, each of which can be brought in such a position as to conveniently feed the thread to the eyes, take-ups, or other devices

employed for leading the thread to the sewing-needle.

A further object of the invention is to economize in the use of spool-cotton and spool-silk by providing a device in which the filled spools may be placed, each being capable of independent rotation and locked in the device until all of the threads have been removed from the spools, thus avoiding the loss of spool thread or silk by the misplacement of the spool or by entanglement of the threads, which loss is experienced to a serious extent by large manufacturers of garments.

An upright rod, post, or standard 10 is provided at its lower end with a thread 30, screwing in the arm B of a sewing-machine. The upper end of the standard is provided with a cap 12. Near the threaded lower end of the standard 10 is secured a cup-like socket 31, provided with a locking-pin 32, preferably spring-actuated and adapted to engage one of a series of apertures 34, formed in the rim of a collar 33, mounted to turn loosely on the said standard and in the said socket, to be locked therein at any desired point by the said locking-pin 32. The collar 33 is secured to the under side of a table 16 of any desired contour and turning with its collar on the standard 10. A series of upright pins or spindles 29 is secured to the table, which pins 80 constitute the axes of the spools A and correspond in number to the apertures 34 in the collar 33.

A cover or locking-plate 18, ordinarily of like contour as the table, is located above the latter and is adapted to revolve around the standard and to be supported on a fixed collar 35 of the standard 10. The under side of the plate 18 when in a lowermost position extends within a short distance of the upper ends of the spindles 29 and spools A, as plainly shown in Fig. 1.

The cover or plate 18 may be locked in place when in a lowermost or uppermost position by a suitable locking device, preferably a lock 22, secured to the under side of the plate 18 and provided with a sliding bolt 21, adapted to engage apertures or annular recesses formed in the collar 35 and the upper end of the standard 10, respectively. The

bolt 21 is preferably actuated by a suitable key 23.

In connection with each spindle 29 a thread-guide 36 is employed, which consists in a metal strip bent to form a horizontal base member d , having an eye d' produced therein for the reception of the spindle and an upright member d^2 , which is carried inward at its junction with the base member at an angle essentially corresponding to the angle of the spool-head, as shown at d^3 , the remainder of the member being perpendicular. The perpendicular section of the member d^2 is provided with a longitudinal slot 37, extending from the top downward, through which slot the thread from the spool is adapted to pass. The guide not only serves as a check upon the rotation of the spool but also prevents the outer layer of thread from falling down upon or over the spool-head and becoming tangled around the spindle. A guide, if desired, may be attached to each of the spindles.

In operation, when the threads have been drawn from the spools in order to replace the empty spools with filled ones, the bolt 21 is shot backward from engagement with the collar 33, and the cover-plate is slid upward upon the standard and the bolt is shot into the upper channel 15 of the standard 10 to hold the cover-plate in an uppermost position. The empty spools may now be readily removed from their spindles and filled spools may be substituted. When the table has been re-filled with full spools, the cover-plate is unlocked from upper end of standard 10 and lowered and secured in its normal position. The space between the table and cover-plate is sufficient to permit the spools to rise upward when the thread is drawn therefrom, but is not sufficient to permit the spools to be removed from their spindles. When the device is applied to the sewing-machine, the table 16 is unlocked by withdrawing the pin 32 from the apertured collar 33, so as to permit turning of the table until the desired spools stand to the left toward the front end of the sewing-machine to deliver the thread to the eyes or take-up mechanisms on the head of

the sewing-machine arm. As soon as the desired position is reached, the locking-pin is again engaged with the corresponding apertures 34 to lock the table in place on the standard 10. When the cover-plate 18 is locked on its lowermost position on top of the spindles 29, and the table 16 is prevented from turning by the spring-actuated pin 32 engaging the apertured collar, then the thread from the spool used at the time is not liable to get entangled in the other spools or the parts of the device, and the spool itself is retained in place on its spindle, an upward movement being prevented by the locked cover-plate and a sidewise motion by the locked table.

It frequently happens that when the thread is quickly pulled or pulled with a jerk the spool tends to move up on the spindle; but a displacement from the latter cannot take place, owing to the position of the cover-plate. Furthermore, such a pull or jerk would cause the table to turn on the spindle were it not for the locking device which holds the table securely in place. The thread can be readily unwound from its respective spool and passed directly to the head of the sewing-machine, for which the device is principally intended.

Having thus described my invention, I claim as new and desire to secure by Letters Patent—

In a device of the character described, the combination, with a fixed standard, of a table mounted to turn on the said standard, spindles secured in the top of the said table, a collar secured centrally on the under side of the said table and provided with apertures corresponding to the number of spindles on the said table, and a spring-pressed locking-pin supported on the said standard and adapted to engage one of the apertures of the said collar to hold the spool to be used in proper position, substantially as shown and described.

CHARLES H. LEWY.
